HUMIDIFIER HAVING CONDUITS WITH
RETURN BENDS

Gottlieb R. Magney, Minneapolis, Minn.

Application June 25, 1932. Serial No. 619,208

12 Claims. (Cl. 257—138)

This invention relates to a humidifying device, and particularly to such a device adapted to be used in connection with a heating element such as a radiator used for heating a room. A great deal of attention is now being given to the problem of keeping the air in living rooms at the proper degree of humidity. Properly humidified air has many advantages and is more healthful than air which is deficient in humidity.

10 It is an object of this invention, therefore, to provide a simple and efficient unit which may be disposed adjacent a heating element such as a radiator, said unit comprising a casing having a lower portion disposed substantially horizontally and having an upper portion connected thereto, said upper portion having an elongated comparatively narrow discharge opening, said latter portion having an opening through which air can pass and into which a fine spray or mist may

15 be projected.

It is a further object of the invention to provide a humidifying unit comprising a tube-like casing having a lower portion with an opening in one end, said casing having a reverse bend at 25 its other end and having an upper portion extending from said reverse bend, said upper portion having a discharge nozzle with an elongated comparatively narrow discharge opening therein, said upper portion preferably being of tapered 30 form.

It is still another object of the invention to provide a humidifying device having in combination with a radiator, a housing enclosing said radiator forming a chamber thereabove, a casing disposed in said chamber having a lower portion extending longitudinally of said radiator with an opening at one end, said casing having an upper portion with a comparatively narrow elongated discharge opening, said housing having 40 an air inlet opening at its bottom and an outlet opening adjacent its top and also adjacent said discharge opening, said casing having means supporting it from said housing, and means directing a fine mist or spray into said opening in 45 the end of said lower portion.

It is more specifically an object of the invention to provide a humidifying structure having in combination with a radiator, a housing enclosing the radiator and forming a chamber thereabove, said housing having an inlet opening for air at its bottom and an outlet opening adjacent its top, a conduit adjacent the radiator and connected thereto at its ends, a casing disposed above said radiator having a lower portion extending longitudinally of said radiator, and an

upper portion having a discharge nozzle with an elongated narrow discharge opening disposed adjacent said outlet opening, a liquid supply pipe passing through said conduit and having a nozzle secured thereto and disposed at one end of said 60 casing directing a fine spray or mist into said casing.

It is a further object of the invention to provide such a device as set forth in the preceding paragraph, together with means for regulating 65 the discharge of liquid from said nozzle in accordance with the temperature in said supply pipe.

These and other objects and advantages of the invention will be fully set forth in the following description made in connection with the accompanying drawings, in which like reference characters refer to similar parts throughout the several views and in which:

Fig. 1 is a vertical section taken for the most 75 part on line 1—1 of Fig. 2, a small portion being shown in front elevation;

Fig. 2 is a section taken substantially on line 2—2 of Fig. 1;

Fig. 3 is a vertical section taken on line 3—3 80 of Fig. 1;

Fig. 4 is a vertical section taken substantially on line 4—4 of Fig. 5, a portion being shown in front elevation;

Fig. 5 is a vertical section taken on line 5—5 85 of Fig. 4; and,

Fig. 6 is a vertical section taken on line 6—6 of Fig. 4, said sections being taken as indicated by the arrows.

Referring to the drawings, particularly Figs. 90 1 to 3, a device is shown comprising a heating element 10 in the form of a radiator. While any form of radiator might be used, in the embodiment of the invention illustrated, a radiator 95 of the type having pipes conducting a heating medium and metal plates such as copper plates extending transversely thereof, is shown. Said radiator comprises the end members or headers 10a and 10b between which extend the pipes 10c which pass through and support a multiplicity of 100 transverse thin metal plates 10d. An inlet or supply pipe 11 is connected to the header 10a, the same being equipped with a regulating valve 12. A discharge pipe 13 is shown connected to the header 10b, the same being equipped with a trap member 14. A pipe or conduit 15 is provided connected at one end by the coupling 16 to the header 10a and connected at its other end to a T-member 20, connected to the top of the header 10b. A relief valve 21 is connected to the top of 110

T-member 20. An aquastat or thermostat 17 of the so-called surface type is secured to conduit 15 adjacent T-member 20. Said member has projecting lugs at its ends about which and 5 the pipe 15 pass the clips 19 securing member 17 to said pipe. A connection 22 is screwed into the side of T-member 20 to which is connected a supply pipe 23 for liquid such as water, and this pipe passes through member 20 and conduit 15.

10 An elbow connection 24 is screwed into the fitting at the end of conduit 15 to which a connection pipe 22a is secured. Pipe 22a extends from member 24 to the strainer member 25, and another short pipe 22b forming a continuation of pipe 22a 15 extends from strainer member 25 to a solenoid valve 26. A housing 27 encloses the radiator 10 having a rear wall 27a, a front wall 27b and end walls 27c extending between the walls 27a and 27b, said housing thus being substantially rectangular in horizontal cross section. Casing 27 has 20 openings 27d at the bottom thereof forming air inlet openings and the front wall 27b is provided with a multiplicity of openings 27e forming outlet openings for air. Said front wall 27b has a depressed panel in which openings 27e are 25 located and also a depressed panel below said panel, said panels being disposed between portions 27f and 27g. A member 27h extends about the top of casing 27 also forming an ornamental 30 bead and forming the top of said casing. Partitions 28 extend vertically between the front and rear walls 27a and 27b some distance from the latter, said partitions extending from the top of the housing 27 and having outwardly extending 35 horizontal portions at their bottoms engaging the tops of the headers 10a and 10b respectively. As shown in Fig. 1, the partitions 28 form chambers at the ends of housing 27 in which are disposed the members 20, 21, 22, the strainer 25 and the 40 fitting 16. A casing 30 is provided, disposed in housing 27 between partitions 28, said casing having a lower portion 30a extending longitudinally of housing 27 and radiator 10. While casing 30 might be variously formed, in the embodiment of the invention illustrated it is shown as 45 tube-like or tubular in form. Portion 30a has an opening at its right hand end as seen in Fig. 1 and a nozzle 31 is connected to valve 26 in position to have a discharge aperture directed 50 into and lengthwise of portion 30a centrally thereof. Nozzle 31 is constructed and arranged to direct a fine spray or mist into portion 30a. Casing 30 is formed with a return bend or reverse 55 bend or elbow 30b and an upper portion 30c extends from portion 30b above portion 30a and thus longitudinally of the housing 27. The lower portion 30a inclines downwardly somewhat toward its left hand end as seen in Fig. 1 and a 60 drain pipe 32 is connected to the lowest portion of said casing, the same extending through one partition 28 and downwardly through the bottom of housing 27. Portion 30c turns upwardly and has secured thereto an upwardly extending and flaring portion 30d, the upper portion of which 65 is quite elongated and in the shape of an elongated rectangle in horizontal cross section. A discharge portion or nozzle 30e extends from the top of portion 30d and as shown in Figs. 1, 2 and 3, this portion extends laterally and has a discharge opening or slot of elongated and comparatively narrow form and is disposed adjacent the openings 27e. Nozzle 30e has a projecting portion 30f at its lower edge and a vertical portion 30g of comparatively small height extends 70 across the discharge opening of said nozzle. Cas- 75 ing 30 has a pair of lugs 30h extending from its top adjacent portion 30d into which are secured the hooks 33. Bars 34 extend across casing 27 adjacent the top thereof having flanges engaging the sides 27a and 27b respectively and secured thereto by suitable bolts or rivets. Rods 35 extend downwardly from the bars 34, said rods having eyelets at their upper ends through which pass the headed and nutted bolts 36 secured in the bars 34, said rods 35 also having eyelets at their lower ends into which hooks 33 engage. The portion 30a of casing 30 has a hook 37 secured in its top adjacent its open end and said hook engages over a rod 38 extending between walls 27a and 27b and supported in lugs 38a thereon. Casing 30 is thus supported so that it can be readily removed by disengagement of the hooks 33 and 37. 80

In operation the pipe 22 will be connected to a source of water under pressure such as the city mains. A heating medium will be supplied to radiator 10 through the pipe 11. The aquastat 17 will be electrically connected to the solenoid valve 26 so that when the temperature of the medium in conduit 15 is at a certain point, 85 the valve 26 will open and water will be projected from nozzle 31. Valve 26 may also be controlled by a thermostat or humidistat disposed in the rooms to be heated. This water will be projected in the form of very fine spray 90 or mist longitudinally of the portion 30a of casing 30. The mist is projected preferably in the form of a cone having its apex at the nozzle and its base substantially at the wall or portion 30a. 95 When the radiator is heated, the temperature 100 within the casing 27 and within the chamber between partitions 28 will be quite high and the air in said chamber will be heated as will also the casing 30. There will be a tendency for the air to rise through the casing 30 and the movement of the air through said casing will be augmented by the spray from nozzle 31. The mist or liquid thus moving through the casing 30 will be thoroughly mixed with the air and taken up 105 thereby and the moisture laden air will pass to 110 the top of casing 30 and be discharged through the opening in nozzle 30e. This air will pass through the openings 27e into the rooms to be treated. The air in housing 27 between partitions 28 is heated by radiator 10 and the air thus 115 rises and passes out through openings 27e, the air entering through the bottom openings 27d. This air passing through the housing 27 mingles with the moisture-laden air issuing from the 120 nozzle 30e and as stated, both pass out through 125 the openings 27e. Any surplus moisture in the form of liquid will drop to the bottom of portions 30a and 30b or will drain back to the portion 30b from the bottom of portion 30c and this moisture will pass out through the drain pipe 32. 130 Should any moisture collect on the walls of portions 30d and 30e, it will also drain back in the portion 30c and pass out through the drain pipe 32. 135 The bottom of portion 30c slopes downward somewhat towards portion 30b. The lip 30g at the end of the nozzle 30e will act somewhat as a baffle to prevent any moisture passing out at the lower edge of the discharge opening or dripping from said edge. When the radiator 10 contains a heating medium, this medium will pass 140 into the conduit 15 and the water supplied in pipe 22 will be heated as said pipe passes through conduit 15. The pipe 22 will preferably be a thin-walled copper pipe and the temperature of the 145 water therein will approximate the temperature 150

in conduit 15. This temperature will actuate the aquastat 17 so that valve 26 will be operated to supply water to nozzle 31 at the desired temperature. The water supplied by pipe 5 22 passes through strainer 25 where all solid matter will be removed. The movement of the air through casing 30 is thus caused both by the natural draft or the natural movement of the heated air upwardly and by the induction of the 10 air caused by the spray from nozzle 31. The air passing out through the openings 27e is thus effectively humidified without any danger of it carrying any excess moisture. By means of the 15 temperature control it is assured that the liquid will not be sprayed by nozzle 31 when there is no chance of its being taken up by the air.

In Figs. 4, 5 and 6 a modified construction is shown. In these figures a radiator 40 is shown and this radiator is illustrated as of the type 20 comprising vertically arranged sections connected at top and bottom, which type has been in common use for heating dwellings. Such a radiator is usually much taller than the type shown in Figs. 1, 2 and 3 and with the housing 27 of substantially the same height there would thus be a smaller chamber in the housing above the radiator. The housing 27 encloses radiator 40 and said housing has the partitions 28 which parts are the same as already shown and described in Figs. 1 to 3. A casing 41 is provided, disposed in the chamber above radiator 40 within the partitions 28 and said casing has a lower portion 41a extending longitudinally of the radiator 40 and housing 27 above said radiator. 25 While casing 41 might take various forms in the embodiment of the invention illustrated it is shown as tube-like or substantially tubular in form. Portion 41a has its bottom sloping downwardly somewhat toward its left hand end as shown in Fig. 4 and a drain pipe 42 leads from the lowest point of portion 41a through one partition 28 and then downwardly out of housing 27 between one partition 28 and one end wall 27c. The casing 41 has a return bend or reversely bent 30 portion 41b and the portion 41c extends from this portion 41b above the portion 41a. Portion 41c also extends longitudinally of the housing 27 and as illustrated is disposed above portion 41a. Portion 41c tapers toward its right hand end as shown in Fig. 4 and said portion has extending 35 from one side thereof a nozzle 41d rectangular in transverse cross section and said nozzle has a discharge opening of comparatively narrow and elongated form disposed adjacent the openings 27e in the front wall 27b. The bottom of nozzle 41d projects somewhat beyond the remainder of the nozzle and a lip 41e extends vertically across the bottom, said lip extending vertically a short distance. The portion 41c is closed at its right 40 hand end as seen in Fig. 4 and the portion 41a is open at its right hand end as seen in said figure. The nozzle 43 is disposed in the end portion of portion 41a, the same being connected to a magnetic valve 44. A water supply pipe 45 is connected to the valve 44. The supply pipe 45 preferably passes through the top of radiator 40 as shown in Fig. 3 so that the water therein will be heated by said radiator. Said pipe also has disposed therein a strainer member 46 disposed 45 between one partition 28 and an end wall 27c. An aquastat or thermostat 47 is secured to the radiator 40 at one end thereof and this will be connected by electrical conductors (not shown) to the magnetic valve 44. Said valve 44 can also 50 be controlled by a thermostat or humidistat in

the rooms to be treated. The casing 41 has secured to the top of portion 41c hooks 48. The hooks 48 are engaged by eyelets at the lower ends of supporting links 49 having eyelets at their upper ends through which pass headed and nutted bolts 50. The bolts 50 pass through and are supported by the bars 51 secured to the side walls 27a and 27b in any suitable manner, as by welding or riveting. The portion 41a of casing 41 also has a hook 52 secured to its top at its free end and this hook engages over a rod 53 supported at its ends on the lugs 54 secured to the inner sides of the walls 27a and 27b. 80

In operation heat will be supplied to the radiator 40 and the pipe 45 will be connected to some source of water under pressure such as the city mains. When the temperature in the radiator 40 reaches the desired point, the valve 44 will be opened by action of the thermostat or aquastat 47 and liquid such as water will be sprayed into nozzle 43 and directed into the open end of portion 41a in very finely divided condition or in the form of mist, said liquid preferably being projected in the form of a cone having its apex at said nozzle and its base at the peripheral wall of portion 41a. As already described, the housing 27 has openings at its bottom and the air in the chamber between partitions 28 will be heated and will pass upward and out through the openings 27e. Air will also naturally pass through the casing 41 and the movement of the air through the casing will be augmented by the spray from nozzle 43. The finely divided water mixes with the air passing through casing 41 and highly humidified air passes from nozzle 41d. This air passing from the nozzle mixes with the air passing up through the casing and out of the openings 27e. Any surplus moisture which might be directed into the casing 41 will drop to the bottom of portion 41a, portion 41b, and portions 41c and 41d and will drain back to the lowest point in said casing and drain out through pipe 42. Pipe 42 will be connected to any suitable drain. The lip 41e at the end of the nozzle 41b insures that no moisture will be carried over the edge so as to drip therefrom. The water sprayed from nozzle 43 passes through the strainer 46 and all solid matter is removed therefrom. Any clogging of the nozzle 43 is thus prevented. 100

From the above description it is seen that applicant has provided a very simple and efficient humidifying device. In both forms shown the interior of the casings, namely casings 30 and 41, will be continuously moist when the device is in operation. This prevents any accumulation of sediment which might be formed from the matter in solution in the water. The shape and size of the casings gives ample opportunity for the moisture sprayed thereinto to thoroughly mix with the air before being discharged. The humidified air being discharged from the nozzles a short distance from the openings in housing 27 gives opportunity for a further mixing of the humidified air with the air passing through the housing which is not humidified. This insures that there will be no possibility of air passing out from housing 27 and being oversaturated. The casings 30 and 41 are arranged so that they can be readily removed when desired. It is only necessary to disconnect the drain pipe and then lift the casings from the supporting means. The hooks by which the casings are supported are readily disengaged from the supporting members. It is apparent that the device can easily and conveniently be installed over standard radiators now 110 115 120 125 130 135 140 145 150

in use. An apparatus which is pleasing in appearance and unobjectionable as living room equipment is thus provided. The device has been amply demonstrated in actual practice and found 5 to be very successful and efficient.

It will, of course, be understood that various changes may be made in the form, details, arrangement and proportions of the parts, without departing from the scope of applicant's invention, which generally stated, consists in a device 10 capable of carrying out the objects above set forth, in the parts and combinations of parts disclosed and defined in the appended claims.

What is claimed is:—

15 1. A humidifying device comprising in combination with a radiator, a casing enclosing and extending about said radiator, a second casing within said casing above said radiator and extending longitudinally thereof, the same having 20 a return bend therein, means for discharging a fine mist or spray into one end of said second casing, the latter having means at its other end for discharging moisture-laden air therefrom.

25 2. The structure set forth in claim 1, said first mentioned casing having an air inlet opening at its bottom and an outlet opening adjacent its top, said last mentioned means being disposed close to said outlet opening.

30 3. A humidifying structure having in combination with a radiator, a housing enclosing said radiator and extending above the same, a casing within said housing disposed above said radiator and being shaped to form a circuitous passage therethrough, said casing having an upper portion 35 provided with a flat discharge nozzle, means for directing a fine mist or spray into the end of said casing opposite said nozzle, whereby air rising from said radiator passes into one end of said casing and moisture-laden air is discharged 40 through said nozzle.

45 4. A humidifying structure having in combination with a radiator, a housing enclosing said radiator having an air inlet opening at its bottom and an outlet opening adjacent its top, a tube-like casing disposed in said housing having a lower portion extending longitudinally of said housing and having an open end, said casing having an upper portion with a relatively narrow discharge opening extending longitudinally of said housing 50 adjacent said outlet opening, and means for directing a fine mist or spray into said open end whereby moisture-laden air is discharged through said discharge opening.

55 5. A humidifying device having in combination with a radiator, a housing enclosing said radiator and forming a chamber thereabove, a casing disposed in said housing having a lower portion extending longitudinally of said radiator, means for directing a fine spray or mist into one end of 60 said portion, said casing having an upper portion connected at one end to the end of said first mentioned portion opposite said means, said upper portion having a narrow discharge opening extending longitudinally of said housing through 65 which moisture laden air is discharged.

70 6. A humidifying device having in combination with a radiator, a housing enclosing said radiator having an air inlet opening adjacent its bottom and an outlet opening adjacent its top, a conduit above and connected at its ends to said radiator, a casing in said housing extending longitudinally above said radiator and having a reverse bend

therein, a liquid supply pipe extending through said conduit, a nozzle connected to said supply pipe and disposed at one end of said casing for directing a fine mist or spray thereinto, said casing having a discharge opening adjacent said outlet opening. 80

7. The structure set forth in claim 6, and means regulating the discharge of liquid from said nozzle in accordance with the temperature of the liquid in said supply pipe. 85

8. A humidifying structure having in combination with a radiator, a housing enclosing said radiator having an inlet opening for air at its bottom and an outlet opening adjacent its top, a casing disposed in said housing having a lower portion extending longitudinally of said radiator having an open end and sloping to its opposite end, a drain pipe leading from said opposite end, said casing having an upper portion extending longitudinally of said housing and connected to said lower portion, said upper portion having a comparatively narrow elongated discharge opening disposed adjacent said outlet opening, and means for directing a fine mist or spray into said open end. 90

9. A humidifying structure having in combination with a radiator, a housing enclosing said radiator having an air inlet opening at its bottom and outlet openings adjacent its top extending longitudinally thereof, a casing in said housing above said radiator, said casing having an elongated comparatively narrow discharge opening extending longitudinally of said outlet openings, said casing having an inlet opening and means for directing a fine spray or mist into said inlet opening. 105

10. A humidifying structure having in combination with a radiator, a housing enclosing said radiator having an air inlet at its bottom and an outlet opening adjacent its top, a casing in said housing above said radiator, said casing having a discharge opening adjacent said outlet opening, said casing having a comparatively large inlet opening below said discharge opening, and means for directing a fine mist or spray into said inlet opening. 115

11. A humidifying structure having in combination with a radiator having a heating medium therein, a housing enclosing said radiator having an air inlet at its bottom and an outlet opening adjacent its top, a casing in said housing above said radiator, said casing having a discharge opening adjacent said outlet opening, said casing having a comparatively large inlet opening below said discharge opening, a nozzle for directing a fine mist or spray into said inlet opening, and means for regulating the discharge of liquid from said nozzle in accordance with the temperature of the heating medium in said radiator. 125

12. A humidifying unit adapted to be positioned above a radiator comprising a hollow casing having a substantially horizontal elongated lower portion with an opening in one end, said casing having a reverse bend at its other end, an upper portion extending from said bend, said upper portion being provided with a nozzle flaring in one dimension and provided with a horizontally disposed elongated flat discharge opening extending substantially parallel to said lower portion. 135

GOTTLIEB R. MAGNEY. 145
